BATHROOM UTILITY RECEPTACLE AND COVER COMBINATION

Marjorie R. Basinais, 2692 11th St.,
Cuyahoga Falls, Ohio

Filed July 29, 1963, Ser. No. 76,011

Term of patent 14 years

(Cl. D4—3)

FIG. 1

FIG. 2

FIG. 3

FIG. 4

FIG. 5

FIG. 1 is a front perspective view of a bathroom utility receptacle and cover combination showing my new design, the combination embodying a cover for a toilet paper dispenser;

FIG. 2 is a cross-sectional view thereof taken on the line 2—2 of FIG. 1;

FIG. 3 is a rear perspective view thereof;

FIG. 4 is a front perspective view of a modified form thereof, the combination embodying a cover for a paper towel dispenser; and,

FIG. 5 is a rear perspective view thereof.

I claim:

The ornamental design for a bathroom utility receptacle and cover combination, as shown.
